**DOWNGLOW HORIZONTAL COOKING
RETORT OVEN**

Joseph van Ackeren, Pittsburgh, Pa., assignor to Koppers Company, Inc., a corporation of Delaware
Filed Aug. 16, 1961, Ser. No. 131,934
9 Claims. (Cl. 202—144)

This invention relates in general to regenerative by-product horizontal coking retort ovens equipped for the well-known reversal of heating of the heating flues in alternation by means of lean fuel gas and high B.t.u. rich fuel gas such as coke oven gas.

More particularly, the invention relates to improvements in high capacity ovens of the aforesaid type having coking chambers of increased height exceeding that of conventional coke ovens by approximately fifty percent and provided with vertical flow passages in partitions between vertical flame flues and flues crossing under coking chambers to permit an increase in the height of the flame flues alongside the coal charge space in the adjacent coking chambers by flow of waste gases off from the vertical flame flues without the use of horizontal bus flues at the tops of the vertical flame flues for such purpose, which bus flues limit the height to which the flame can be carried up alongside the coking chambers by combustion of fuel gas in the vertical flame flues.

The invention has for a principal object: a more simple flue construction that eliminates the need for upfiring of the vertical flame flues with rich fuel gas and which permits downfiring instead from mains and headers accessible on the oven battery roof, thereby greatly reducing the cost of construction and maintenance of this type of oven.

A further important object of the invention is the provision, in conjunction with such topfiring of the flues with rich fuel gas, of a novel gas flow connection between the regenerators and the flues which permits the introduction of regenerator air or air and lean gas to the flues and off-flow of waste gas from the flues to the regenerator through ports at a multiplicity of vertically spaced levels along the entire height of the flues from riser passages in the vertical partitions between the vertical flame flues in each heating wall. The advantage of this latter feature is that the total quantity of fuel gas, whether rich or lean fuel gas, is initially ignited only in small amounts at a multiplicity of closely spaced levels throughout the entire height of the heating flues. In this manner all parts of the coal charges throughout their height in the adjacent coking chambers are uniformly heated without a marked reduction in coke quality and without need for recycling inert or waste gas into the rich gas to dilute it to produce a long lean flame like that produced from the regeneratively preheated lean gas when optionally used to fire the flues in lieu of rich gas like coke oven gas.

Accordingly, the invention provides for this purpose duct means crossing under intervening coking chambers and communicably connecting the bottoms of the flame flues in one heating wall individually with the bottoms of the flame flues in the heating wall on the opposite side of an intermediate coking chamber and riser passages in the partition walls between the individual flame flues therein with ports therefrom to the two flues separated by the partition wall. These ports are disposed at closely spaced levels, from bottoms to the tops of the flame flues. The riser passages of alternate partition walls are communicably connected at their bottoms with one regenerator of a pair and the riser passages of the intermediate partition walls in each heating wall are connected with another regenerator of a pair.

2

The rich fuel gas is supplied to each heating flue solely at the tops thereof by means of individual vertical gas supply branch ducts in the oven roof which are fed with coke oven gas by means of a series of mains or headers, one for each heating wall supported at the top surface of the oven battery.

In addition to the general objects recited above, the invention has for further objects such other improvements and advantages in construction and operation as are found to obtain in the structures and devices hereinafter described or claimed.

In the accompanying drawings forming a part of this specification and showing, for purposes of exemplification, a preferred form and manner in which the invention may be embodied and practiced, but without limiting the claimed invention to such illustrative instance or instances:

FIGURE 1 is a composite vertical sectional elevation taken longitudinally of the coke oven battery, in planes indicated by the lines C—C and D—D of FIG. 2;

FIG. 2 is a vertical section taken crosswise of the battery and longitudinally of a heating wall in a plane indicated by the lines A—A and B—B of FIG. 1; and

FIG. 3 is an horizontal section taken in a plane indicated by the line E—E of FIG. 1.

The same characters of reference designate the same parts in each of the several views of the drawings.

In the embodiment illustrated in the drawings, the invention is incorporated in a combination coke oven battery, i.e., a battery having provision for being operated either with blast furnace gas as the fuel or with coke oven gas burned in an atmosphere of ordinary preheated air, which is introduced into the flame flues separately from the gas.

For convenience, the present description will be confined to the present illustrative embodiment of the invention in such a combination oven battery; the novel features and improvements of the invention are, however, capable of other applications, such for example, to ordinary so-called "coke ovens" employing coke oven gas as the fuel; hence, the scope of the invention is not confined to the specific use and specific embodiment herein described as an illustrative example.

Referring to the drawings: there are illustrated views of a chemical recovery coke oven battery or plant of the by-product type having features above specified; said oven battery embodies in its construction a plurality of crosswise elongated heating walls 11, and a plurality of intermediate crosswise elongated vertical coking chambers 12, 16, as shown in FIG. 1. The heating walls 11 are directly supported by the heavy supporting or pillar walls 13, 13 which extend crosswise of the battery and are located, as shown in FIG. 1, beneath the respective heating walls 11. These pillar walls, together with other walls 22, hereinafter described, collectively form the main support for the entire superstructure of the oven battery and are themselves supported upon a flat mat or platform, not shown, which constitutes the subfoundation on which the entire battery rests. The coal to be coked is charged into the several coking chambers or ovens through the charging holes 14, located in the top 15 of the battery and positioned directly above the ovens or chambers 12, 16, as shown in FIGS. 1 and 2. These charging holes 14 are equipped with the usual removable covers, not shown, which are removed during charging of the individual ovens or coking chambers and are placed in position to close the tops of such coking chambers during the entire coking or distilling operation. The gases of distillation pass from the tops of the several coking chambers through the gas outlets, not shown, and thence through ascension pipes, not shown, into the usual gas

collecting main which carries the distillation products to the by-product chemical recovery apparatus.

Heat for coking the several charges of coal in the several ovens or chambers 12, 16, is derived from the heating walls 11 at the sides of the coking chambers. Each heating wall 11 is constituted of a plurality of flame or combustion flues 17. The flame flues of each heating wall are, in accordance with the invention, operatively disposed into a single series, that is to say, all of the flues of each heating wall operate concurrently as downflow or upflow flues, as will be hereinafter more fully explained. With regard to the flow through the flues, the heating walls are disposed into two groups L and M. The pairs of the heating walls of the group L alternate with the pairs of heating walls of the group M. When the flame flues of the group of alternate pairs of heating walls L are burning for downflow, the flame flues of the intermediate pairs of heating walls of the group M are operating for upflow of the waste gases. With this system of flow, when the flame flues on both sides of one of two alternate coking chambers 12 are burning, the flame flues on both sides of the other of two consecutive alternate coking chambers 12 are operating for upflow of waste gas, and when the flame flues on one side of each intermediate coking chamber 16 are burning, the flame flues on the opposite side of the same coking chamber 16 are operating for upflow of waste gas, the same system of flow taking place uniformly throughout the battery.

Each regenerator 18 is a chamber containing open brick work, commonly called checker brick, and indicated at 20 with a distributing sole channel 21 underneath such checker work, the channels forming the soles of such chambers and opening up into the checker work. As shown, a heavy vertical gas-tight supporting wall 22 extends directly beneath each intermediate coking chamber 16 in parallelism between each two pillar walls 13, and such supporting walls 22 provide two regenerators located respectively on the opposite sides of such walls 22 and between adjacent pillar walls 13. The several walls 22 also have the function, with the pillar walls 13, of supporting the weight of the battery superstructure. No such vertical supporting wall is provided underneath the alternate coking chambers 12 in order to leave wide regenerators between each two pillar walls 13 for each pair of heating walls L or M.

This supporting wall construction provides two series of crosswise extending gas-tight, load-carrying walls, located below the coking chambers and intermediate heating walls, which function not as mere partitions as commonly employed, but as true load-carrying, gas-tight walls, permitting relatively different pressures to be maintained in the checker work chambers on the opposite sides of such walls, and the flow of different media in the checker work chambers separated by these walls without leakages from one checker work chamber into another and without danger of mixing gases in the checker work chambers which must be kept separate in this region of the battery.

These series of regenerators are operatively grouped into a set L' of alternate regenerators corresponding individually to the individual pairs of heating walls of the groups L and into a set M' of the intermediate regenerators respectively corresponding to the individual pairs of heating walls of the groups M. Each regenerator of a set L' or M' is provided with a series of regenerator ducts 23, and the ducts of both regenerators of a pair are respectively individual flame flues of the same corresponding heating wall; so that a flame flue 17 communicates directly by a pair of ducts 23 with adjacent separate regenerators, through which however flow is maintained concurrently in the same direction, that is to say, both said regenerators are either operating for inflow or outflow.

In the present embodiment of the invention, the entire series of flame flues 17 of each heating wall 11 operates

in alternation either for downflow burning of gases or for upflow of waste gases of combustion from an adjacent heating wall to convey the waste gas products to the regenerators beneath. The reversal in flow through the flues 17 on opposite sides of the coking chambers and into communicably connected regenerators thus takes place longitudinally of the battery instead of transversely thereof, as has been a common practice in this art. The reversal of the battery is effected at the end of an operating period determined by practice and by means of any preferred known type of reversing mechanism, not shown. The function of such reversal is as follows: The regenerators that prior to the reversal operated as inflow regenerators become outflow regenerators, and the outflow operating regenerators become inflow operating regenerators. The downflow burning series of flues switches function with the upflow waste gas series of flues and the supply of gas is turned off from the previously downburning flues and turned on into the mains of the previously upflow waste gas flues 17.

In accordance with the present invention, to simplify the costs of construction, operation and maintenance, all rich gas is fed to the individual heating flues solely at their tops, by means of branch pipes in the top of the battery which are fed from mains on the battery roof. To this end, extending crosswise of the battery and located above the heating walls 11 therebelow, are gas supply headers 31. These headers are for supplying coke oven gas to the several flame flues 17. The headers 31 communicate with the individual flues 17 by means of ducts 33 that lead from the headers 31 individually into the tops of individual flues 17. Within the several ducts are disposed the usual nozzles 34, and within the battery roof are also shown the tie rods 32.

The supply of coke oven gas to the respective headers 31 is derived from the coke oven gas mains of the usual type located in the roof area of the battery and extending longitudinally therealong. Suitable means is provided for admitting or cutting off the supply of gas with respect to each channel 31, it being understood that the gas supply is either concurrently maintained in or concurrently shut off from the headers 31 for the flame flues 17 of the two sets L and M. For operating the battery alternatively with the use of a lean gas such as producer gas or a blast furnace gas, as the fuel, one regenerator of each inflow operating pair, such as the regenerators G of the group L' may be optionally connected with a lean gas main by mechanism such as is disclosed in the prior art, so that lean gas may be directed into such of the regenerators G as are operating for inflow, for conveying through these regenerators lean gas into the burning flame flues 17.

Also, in accordance with this invention, to provide for uniform flame heating throughout the entire height of the coal charges in the coking chambers, with even heating throughout such entire height by means of rich gas, air is introduced and waste gas is withdrawn at a multiplicity of levels by means of ports 26 leading to the riser passages 37 in partition walls 25 between the flame flues 17. Said riser passages 37 lead to the regenerators through the regenerator ports 23 to receive air from the regenerators and to discharge the waste gas thereto. The waste gas from each flue 17, when operable for downflow combustion of the rich fuel gas from nozzles 34, or lean gas from the ports 26 in alternate ones of the partition walls 25, is passed through crossunder ducts 28 to the bottoms of flue 17 in another heating wall for upflow in their flues to their ports 26 in all of the partition walls 25, whence they flow to the riser passages 37 and down into the regenerators 18.

As shown in FIGS. 2 and 3, the series of flues 17 of each heating wall are provided with separating walls 25 between each two such flues, which terminate at the top of the flues, thereby eliminating outflow passageways for the exhaust of the products of combustion at the tops

of the flues. The separating walls 25 are each provided with a vertical riser passage 37 communicably connected at their bottoms with the respective regenerator ducts 23 leading downwardly into the regenerators. The cross ducts 28 extend beneath the intermediate coking chamber 16 and function to connect the downflow flues 17 of each heating wall of the group L with the corresponding flues 17 of the next adjacent heating wall of the group M. Thus the entire flow from the heating wall within the flues of which downflow combustion is being maintained, pass under an intervening coking chamber through ducts 28 to the bottom of the vertical flues 17 of an adjacent heating wall, thence up through said flues 17 to the riser passages 37 and thence downwardly through the riser passages to the outflow operating regenerators with which said flues are connected.

The draft through the flues 17 may be regulated by means of the usual removable dampers or sliding bricks 29 located in the crossunder ducts 28 at the base of the respective flues. These sliding bricks may be reached by access flues 30 which extend through the top 15 of the battery, there being an access flue positioned over each flame or combustion flue 17 of each heating wall 11.

The flow of waste gas off from the bottom of each flame flue 17, through the crossunder flues 28, into the bottoms of flame flues then operable for off-flow of waste gas through the ports 26 in their partition walls 25, permits off-flow of waste gas without passages which otherwise would limit the height to which flame could be conducted alongside the coal charges in their adjacent coking chambers, 12, 16. Hence, flame may be carried from the top level 19 for finished coked coal charges, on down to the bottom of the flues, of coal charged in up to the upper top level 19^a, which is the level of the bottom of the usual leveler doors at one of the horizontal ends of these horizontal coking retort ovens.

The heating wall sets L and M comprise two sets of heating walls forming a consecutive series of groups, longitudinally of the battery (transversely as seen in FIG. 1). Each group comprises a heating wall of a set L connected through a crossunder duct 28 with a next adjacent heating wall of a set M as seen in the left hand side of FIG. 1.

To provide for lean gas underfiring in lieu of rich gas firing, the regenerators are shown as disposed for operation in groups of three regenerators each, comprising a middle wide regenerator G for inflow of lean gas, and two narrow regenerators A for concurrent inflow of air. These regenerators when operable for outflow, all operate as regenerators W for waste gas outflow to a tunnel and stack (not shown) through the sole channels 21. Each wide regenerator G communicates with the flame flues of two heating walls through the regenerator ports 28, which lead only to the riser passages 37 in alternate partition walls whereas the narrow regenerators A each communicate with the flame flues in only one of the same two heating walls through their regenerator ports 28, which lead to the riser passages 37 in the intermediate partition walls 25 in each heating wall 11. The ports 26 lead from each riser passage 37 into both flues on opposite sides of each partition wall, so that the regenerators A and G communicate with all flues 17, when these walls are operable for downflow combustion, so that each flue is flame heated by either rich fuel gas or lean fuel gas by means of a less costly and simple, economical and facile regenerator gas flow construction.

The operation of the battery when employing lean gas, such as blast furnace or producer gas as the fuel is as follows: the supply of coke oven gas to the coke oven gas main and to all of the coke oven gas headers 31 is cut off. A supply of lean gas is permitted to flow into one regenerator G of each of the inflow operating groups such as the set L'. Passing through said regenerators, the lean gas is preheated before being delivered into the riser passages 37 for delivery to the ports 26 in the alter-

nate partition walls for burning in the flame flues 17. During the inflow of lean gas into such regenerators G, air flows into the other regenerators A of said inflow operating set L' and passing through said regenerators is preheated prior to its delivery into the riser passages 37 for delivery to the ports 26 in the intermediate partition walls 25 for the burning flame flues, such as the flame flues of alternate pairs of heating walls L. In the flame flues of the intermediate pairs of heating walls M, upflow is maintained into the ports 26 whence the gas passes down through the riser passages 37 to the intermediate groups of regenerators M', wherein downflow is maintained, said regenerators M' operating as waste gas regenerators W. The flame flues of the walls M receive the waste gases from the before-mentioned crossunder ducts 28. On reversal of the flow, the inflow operating regenerators and flues become outflow operating regenerators and flues and concurrently the outflow operating regenerators and flues become inflow operating regenerators and flues.

In operating the battery with unpreheated rich fuel gas, such as coke oven gas, the supply of lean gas to the regenerators G is cut off and air is permitted to flow into such regenerators in place of the lean gas. During such coke oven gas operation a supply of coke oven gas is maintained in the headers 31 which feed the downburning flues. The reversing mechanism, not shown, is operated at each reversal to place each of the inflow operating regenerators in communication with the outer air and concurrently all of the outflow operating regenerators W in communication with the exhaust.

The novel mode of operation with coke oven gas as the fuel eliminates the need for supply of a neutral gaseous diluent to the burning flues. In operating the battery, the supply of rich gas solely at the top of each flame flue together with the admission of regenerator air into the downburning flame flues at a multiplicity of levels is effective to lengthen greatly the flames within such flues and to prevent the localization of the hottest flame temperature in the extreme upper portion of the flues, since only a very small portion of the total gas is ignited at each of the levels of each of the ports 26. The entire height of the coal charges is flame heated since the crossunder ducts 28 take off the waste gases from the flues at a level below the bottoms of the coal charges but above the tops of the regenerators.

The invention, as hereinabove set forth, is embodied in a particular form of construction, but may be variously embodied within the scope of the claims hereinafter made.

I claim:

1. In a coke oven battery, in combination: a series of alternate horizontal coking chambers and intermediate heating walls arranged side by side in a row, each of said heating walls having a row of vertical flame flues with vertical partition walls between and separating each two flues, a vertical riser passage in each of said partition walls, a plurality of ports leading from each of said passages connecting each of said passages with a pair of flues in said heating wall at a plurality of closely spaced levels along the height of the flues, crossunder duct means passing beneath intervening coking chambers and communicably connecting the bottom ends of the flame flues in each heating wall solely with the bottom ends of the flame flues in one other heating wall, and regenerators communicably connected with the bottom ends of the vertical riser passages in said partition walls said regenerators extending parallel to said heating walls.

2. Apparatus as claimed in claim 1, and which includes rich gas headers in the region of the top of said battery, branch ducts extending down through the top of the battery and terminating solely at the tops of the flame flues, said branch ducts connecting said gas headers with said flame flues solely for supply thereto of rich fuel gas.

3. Apparatus as claimed in claim 1, and in which the regenerators are directly connected in pairs with the flame flues of the heating walls through the aforesaid bottom ends of the vertical riser passages in said partition walls.

4. Apparatus as claimed in claim 1, and which includes rich gas headers in the region of the top of said battery, branch ducts extending down through the top of the battery and terminating solely at the tops of the flame flues, said branch ducts connecting said gas headers with said flame flues solely for supply thereto of rich fuel gas, and in which the regenerators are connected in pairs directly with the flame flues of the heating walls through the aforesaid bottom ends of the vertical riser passage in said partition walls.

5. In a coke oven battery, in combination: a series of alternate horizontal coking chambers and intermediate heating walls arranged side by side in a row, each of said heating walls having a row of vertical flame flues with vertical partition walls between and separating each two flues, a vertical riser passage in each of said partition walls, a plurality of ports leading from each of said passages to each of the flame flues separated by the partition walls at a plurality of closely spaced levels throughout the height of the flues, crossunder duct means passing beneath intervening coking chambers and communicably connecting the bottom ends of all of the flame flues in each heating wall solely with the bottom ends of the flame flues in one other heating wall, and regenerators extending parallel to said heating walls communicably connected in pairs with the bottom ends of the vertical riser passages in said partition walls, one regenerator of each pair being communicably connected directly with the riser passages in alternate partition walls in a heating wall and the other regenerator of the same pair communicably connected with the riser passages in the intermediate partition walls in the same heating wall.

6. Apparatus as claimed in claim 5, and which includes rich gas headers in the region of the top of said battery, branch ducts extending down through the top of the battery and terminating solely at the tops of the flame flues, said branch ducts placing said gas headers in communication with said flame flues solely for supply thereto of rich fuel gas.

7. In a coking retort oven battery, in combination: a series of horizontal coking chambers and intermediate heating walls; each heating wall comprising a row of vertical flame flues, vertical partition walls between and

defining the flues, vertical riser passages in the partition walls, and ports leading from the riser passages to the flues connecting each of said passages with a pair of said flues at a plurality of levels; said heating walls being operatively disposed into adjoining alternate and intermediate pairs of heating walls for inflow flame heating and outflow of waste gases of combustion in alternation by having the bottoms of the flame flues of each heating wall of a pair of heating walls disposed on opposite sides of each alternate coking chamber communicably connected solely with the bottoms of the flues in the heating wall alongside the next adjacent intermediate coking chamber by means of crossunder ducts passing underneath the intermediate coking chambers; regenerators below the cooking chambers and heating walls extending parallel thereto and operatively disposed in two sets of alternate and intermediate regenerators for concurrent inflow and outflow in alternation in correspondence with said adjoining pair of heating walls, and regenerator ducts in the masonry beneath the alternate coking chambers for communicably directly connecting the alternate and intermediate regenerators respectively with riser passages in the alternate and intermediate pairs of heating walls aforesaid.

8. Apparatus as claimed in claim 7, and which includes rich gas headers in the region of the top of said battery, branch ducts extending down through the top of the battery and terminating solely at the stops of the flame flues, said branch ducts connecting said gas headers with said flame flues solely for supply thereto of all non-regeneratively preheated rich fuel gas.

9. Apparatus as claimed in claim 7, and in which the regenerators are directly connected in pairs with the flame flues of the heating walls through the aforesaid bottom ends of the vertical riser passages in said partition walls.
